UNITED STATES PATENT OFFICE.

STACY B. HART, OF PEORIA, ILLINOIS, ASSIGNOR TO THE HART WEIGHER COMPANY, OF SAME PLACE.

TWO-WAY PIVOTAL COUPLING.

SPECIFICATION forming part of Letters Patent No. 627,260, dated June 20, 1899.

Application filed March 3, 1898. Serial No. 672,371. (No model.)

To all whom it may concern:

Be it known that I, STACY B. HART, a citizen of the United States of America, residing at Peoria, county of Peoria, and State of Illinois, have invented certain new and useful Improvements in Two-Way Pivotal Couplings, of which the following is a description.

Referring to the accompanying drawings, wherein like reference-letters indicate like or corresponding parts, Figure 1 is an elevation of a two-way pivotal coupling embodying my improvements. Fig. 2 is a section in line 2 2 of Fig. 1. Fig. 3 is a section in line 3 3 of Fig. 1. Fig. 4 is a similar section showing a modification. Fig. 5 is an end view of a grain-separator, showing my device as applied to the elevator-tube, the dot-lines showing the elevator with the foot swung outward from the machine to clear the wheels and other parts when folding down upon the top of the separator; and Fig. 6 is a side view of a grain-separator, showing in dotted lines the grain-elevator in the act of folding down upon the top of the machine.

The object of my invention is to provide a simple, effective, and economical two-way hinge, joint, or coupling device for use in any case where it is desired to give a part a double movement, the two being at an angle to one another. My invention accomplishes this in a satisfactory manner; and it consists in the novel construction and combination of parts shown and described, and particularly pointed out in the claims.

I have shown my invention as applied to the elevator-tube of a grain-separator and will describe its use as thus applied; but I do not wish to limit myself to such use, as it is equally well adapted for use for many other purposes.

In the drawings, A represents the grain-separator, provided with a transverse bar or pipe B, (preferably a gas-pipe of suitable size,) extending partly or entirely across the top of the machine and adapted to support the elevator-tube C.

My improved device is adapted to form the connection between the elevator-tube and the support B. For this purpose I provide a separable sleeve D, composed of the parts d and d' and provided with means to tempo-

rarily hold the two parts in proper relation to one another. The sleeve is of a suitable size to embrace the bar or pipe support B, and a nut or bolt E, connecting the parts d and d', furnishes the means to firmly clamp the sleeve to the support when desired. The foundation for the sleeve is a plate F, forming one part of the sleeve D, to which the movable part of the sleeve may be pivotally connected or hinged, as shown at d², or otherwise suitably connected.

A second plate G, to which the elevator-tube is firmly secured and against the face of which preferably the face of the plate moves, forms the base of the entire device. A bolt H, loosely extending through the plates G and F, permits the necessary movement of the two plates to form the pivotal action desired.

The mode of operation is as follows: The plate G, carrying the other parts, is firmly secured to the elevator-tube in any preferred manner—as, for example, by a loop or staple embracing the elevator-tube, to the legs k k of which the plate is bolted. The device is then mounted on the machine by passing the sleeve D over the protruding end of the supporting bar or pipe B, which connection is also pivotal in its nature, as upon loosening the nut or bolt E it permits the sleeve to slip or rotate upon the support. When the elevator-tube is in its working position, (shown in full lines in Fig. 5,) the sleeve is firmly clamped to the support, and the lower end of the elevator tube or foot is also temporarily secured to the machine in any preferred manner. When it is desired to turn the elevator-tube down upon the top of the machine for transportation purposes or for the purpose of passing the machine through a low door, or for any other purpose, the elevator-tube is disconnected at its bottom from the machine and the foot swung outward, Fig. 5, to clear the wheels and other obstructions on the machine.

The nut or screw E is then loosened by the handle e or other means, and the elevator-tube may then be rotated on the sleeve-and-support connection, Fig. 6. The elevator may then be laid down upon the top of the machine and secured in any suitable manner.

Having thus described my invention, what

I claim as new, and desire to secure by Letters Patent, is—

1. The combination with a supporting-bar, of a two-way pivotal coupling comprising a member G provided with means for securing it to a part, a member F pivotally connected to said member G, a member d hinged to said member F and constituting with it a sleeve embracing said supporting-bar, and a clamping means for clamping said members F and d on said supporting-bar, substantially as described.

2. In a two-way pivotal coupling, the combination of a cylindrical supporting-bar, a member G provided with means for securing the same to a part of a machine and having

a flat face, a member F having a flat face working on said flat face of the member G and having a substantially semicircular bearing for said cylindrical supporting-bar, a bolt 20 pivotally securing said members F and G together, a member d hinged to said member F and having a complementary bearing for said supporting-bar, said members d and F constituting a two-part sleeve embracing said 25 supporting-bar, and a hand clamping device for clamping said sleeve onto said supporting-bar, substantially as described.

STACY B. HART.
